(57) **CLAIM**

The ornamental design for a shoe management apparatus, as shown and described.

DESCRIPTION

FIG. 1 is a front perspective view of the shoe management apparatus showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the area '8' as identified in FIG. 1;

FIG. 9 is a partial enlarged view of the area '9' as identified in FIG. 1; and,

FIG. 10 is an exploded perspective view thereof.

The broken lines depict portions of the shoe management apparatus that form no part of the claimed design. The dash-dot lines illustrate the boundary of the enlarged views and form no part of the claimed design.

1 Claim, 10 Drawing Sheets
